UNITED STATES PATENT OFFICE.

THOMAS A. HENLEY, OF ENOLA, ARKANSAS, ASSIGNOR OF ONE-HALF TO JESSEE M. REYNOLDS, OF VILONIA, ARKANSAS.

STALK-CUTTER.

970,709.

Specification of Letters Patent. Patented Sept. 20, 1910.

Application filed March 15, 1910. Serial No. 549,427.

To all whom it may concern:

Be it known that I, THOMAS A. HENLEY, a citizen of the United States, residing at Enola, in the county of Faulkner and State of Arkansas, have invented a new and useful Stalk-Cutter, of which the following is a specification.

This invention relates to stalk cutters, and one of its objects is to provide a machine of this type having a revolute cutting element flexibly supported, and under the control of elastic pressing means which serve to hold the said element yieldingly in contact with the ground.

15 A further object is to provide a cutting element including a body capable of being utilized as a roller, there being a series of blades detachably connected to said body.

20 A further object is to provide a cutting element so mounted as to readily yield when moved against an obstruction.

25 With these and other objects in view, the invention consists in certain novel details of construction and combinations of parts hereinafter more fully described and pointed out in the claims.

In the accompanying drawings, the preferred form of the invention has been shown.

In said drawings:—Figure 1 is a plan view of a machine embodying the present improvements. Fig. 2 is a side elevation thereof. Fig. 3 is a section on line A—B of Fig. 2. Fig. 4 is a side elevation of a portion of a slightly modified form of machine. 35 Fig. 5 is a section on line C—D of Fig. 4.

Referring to the figures by characters of reference, 1 and 2 designate the front and rear axles of the machine, each axle being carried by supporting wheels 3 and the two 40 axles supporting a frame 4 on which the driver's seat 5 is mounted. An arcuate guard 6 is supported upon the frame 4 and under and back of the seat, the same serving to prevent portions of stalks, etc., from being violently thrown against the driver during the operation of the machine. As 45 shown in Fig. 1, the guard extends practically throughout the width of the frame 4.

An auxiliary frame 7 is disposed below the main frame 4 and between the front and

rear wheels 3, this auxiliary frame being supported at its front end by upper and lower rods 8 and 9 respectively, connected by means of turn buckles 10, the upper rods being pivotally attached to the main 55 frame 4 while the lower rods are pivotally connected to the auxiliary frame. The rear end of said auxiliary frame is pivotally connected to the main frame by means of chains 11, or other flexible devices, the said chains 60 and rods being so disposed as to converge downwardly as clearly indicated in Fig. 2.

Each side of the auxiliary frame 7 has a downwardly and forwardly inclined hanger 12 provided with a longitudinal slot 13 and 65 slidably and revolvably mounted within these slots are trunnions 14 extending from the ends of a roller 15. Each of these trunnions 14 is journaled within the lower end of a bar 16, the upper end of which has a 70 head 17 slidably mounted on guide rods 18. These rods have an integral stem 19 at their upper ends, said stem extending through and being attached to the guard 6, the connection being such as to permit a slight swinging 75 movement of the stem 19 relative to the guard. A coiled spring 20 extends around the guide rods 18 and bears at one end against the guard 6 and at its other end against the head 17. As shown in Fig. 1, a 80 rod 16, guide rods 18 and spring 20 are provided at each side of the machine and it will be found that the spring, by exerting a constant downward pressure against the head 17, serves to hold the trunnions 14 normally 85 in position at the lower ends of the slots 13. Chains or other flexible devices, such as indicated at 21, are attached to the trunnions 14 and extend upward to and are designed to be wound upon drums 22, each of which 90 is provided with a ratchet lever 23 whereby it can be conveniently rotated. By means of these drums and ratchet levers, the auxiliary frame and the parts connected thereto can be elevated relative to the main frame 4 95 so as to lift the roller 15 out of contact with the ground.

A star wheel 24 is secured to each end of the roller 15, the points or fingers of this wheel extending a short distance beyond the 100

periphery of the roller and being sufficiently wide to receive a bolt or other fastening device, such as indicated at 25, for the purpose of holding cutting blades upon said projecting points.

In the form of machine shown in Figs. 1 and 2, a draft tongue 27 is connected to the front axle 2, but it is to be understood, if preferred, thills or shafts 28 may be connected to 10 the front axle as indicated in Figs. 4 and 5.

When the machine is drawn forward, the roller 15 presses downward on the ground and at the same time the blades 26 cut the stalks, it being understood of course, that 15 the roller and the blades are pressed downwardly yieldingly by the springs 20 which push against the heads 17 and thus cause the bars or rods 16 to force the trunnions 14 downwardly within the slots 13. Should the 20 roller and its blades come into contact with an obstruction, the said roller and blades will be capable of moving upwardly a distance equal to the length of the slots 13 but should this distance be insufficient to permit 25 the roller to pass over the obstruction, further upward movement of said roller is permitted in view of the fact that the auxiliary frame 7 is carried by flexible supports capable of swinging upwardly.

30 Inasmuch as the guide rods 18 and their stems 19 are capable of swinging relative to the shield 6, it will be apparent that the rods 16 will not prevent the upward swinging movement of the auxiliary frame 7.

35 If desired, the blades 26 can be removed from the points of the star wheels as shown in Fig. 4, it being thus possible to use the machine solely for rolling.

If desired, and as shown in Fig. 5, drag 40 bars may be pivotally connected to the front axle of the machine so as to straighten out the stalks as the machine moves forward and bring them into position to be severed by the cutting blades. These guide blades 45 have been designated by the numeral 29. A foot rest or brace may be placed upon the top portion of the frame.

Various changes can of course be made in the construction and arrangement of the 50 parts without departing from the spirit or sacrificing the advantages of the invention.

What is claimed is:

1. In a machine of the class described, a wheel supported main frame, an auxiliary frame, downwardly swinging connections between the main and auxiliary frames, an element slidably and revolvably mounted within the auxiliary frame, and a spring controlled means for exerting a constant pressure upon the element.

2. A machine of the class described including a wheel supported main frame, an auxiliary frame therebelow, adjustable connections between the front portions of the

auxiliary frame and the main frame, flexible connections between the rear portion of the auxiliary frame and the main frame, an element slidably and revolvably mounted within the auxiliary frame, and means carried by the main frame for exerting a constant downward yielding pressure upon the element.

3. In a machine of the class described a wheel supported main frame, an auxiliary frame therebelow and mounted for swinging movement relative thereto, longitudinally slotted hangers extending from the auxiliary frame, a soil engaging element, trunnions extending therefrom and slidably and revolvably mounted within the slotted hangers, and spring pressed means carried by the main frame for exerting a constant downward pressure upon the trunnions.

4. A machine of the class described including a wheel supported main frame, a guard thereon, an auxiliary frame mounted for swinging movement relative to said frame, hangers depending from the auxiliary frame, a soil engaging element, trunnions thereon, slidably and revolvably mounted upon the hangers, and spring pressed means carried by the guard for exerting a constant downward pressure upon the trunnions.

5. A machine of the class described including a wheel supported main frame, a guard thereon, an auxiliary frame, longitudinally adjustable connections hingedly attached to the main frame and to the front portion of the auxiliary frame, flexible connections between the rear portions of the auxiliary frame and the main frame, hangers depending from the auxiliary frame, a soil engaging element, trunnions thereon mounted for sliding and rotary movement within the hangers, and spring pressed means carried by the guard for exerting a constant downward pressure upon the trunnions.

6. In a machine of the class described, a wheel supported main frame, an auxiliary frame, longitudinally adjustable connecting rods pivotally attached to the main and auxiliary frames, flexible connections between the main and auxiliary frames, said rods and flexible connections converging downwardly, a shield upon the main frame, a revolvable element carried by the auxiliary frame, means upon the shield for elevating the auxiliary frame relative to the main frame, and spring controlled means carried by the shield for exerting a constant downward pressure upon the revolvable element.

7. A machine of the class described including a wheel supported main frame, an auxiliary frame, swinging connections between the main and auxiliary frames, a revolvable element slidably and revolvably

mounted within the auxiliary frame, means supported by the main frame for successively elevating the revolute element within the auxiliary frame and for elevating said auxiliary frame relative to the main frame, and spring controlled means carried by the main frame for exerting a constant pressure upon the revolute element.

In testimony that I claim the foregoing as my own, I have hereto affixed my signature 10 in the presence of two witnesses.

THOMAS A. HENLEY.
